UNITED STATES PATENT OFFICE

172,035

AIR SCOOP

Frederick A. Krusemark, Oak Park, Ill.

Application January 25, 1954, Serial No. 28,658

Term of patent 14 years

(Cl. D14—6)

To all whom it may concern:

Be it known that I, Frederick A. Krusemark, a citizen of the United States and a resident of the village of Oak Park, county of Cook, State of Illinois, have invented a new, original, and ornamental Design for an Air Scoop, of which the following is a specification, reference being had to the accompanying drawing, forming a part thereof, in which:

Figure 1 is a perspective view of an air scoop embodying my new design;

Figure 2 is a top plan view;

Figure 3 is a front end elevation;

Figure 4 is a side elevation; and
Figure 5 is a rear end elevation.

I claim:

The ornamental design for an air scoop, substantially as shown.
